UNITED STATES PATENT OFFICE.

CHARLES OWENS, OF CHATTANOOGA, TENNESSEE, ASSIGNOR OF ONE-HALF TO D. P. MONTAGUE, OF CHATTANOOGA, TENNESSEE.

MOVEMENT-CURE APPARATUS.

SPECIFICATION forming part of Letters Patent No. 752,252, dated February 16, 1904.

Application filed April 18, 1903. Serial No. 153,291. (No model.)

To all whom it may concern:

Be it known that I, CHARLES OWENS, a citizen of the United States, residing at Chattanooga, Hamilton county, Tennessee, have invented certain new and useful Improvements in Movement-Cure Apparatus, of which the following is a specification.

My invention is an apparatus for the treatment of diseases; and it consists in the features and combination and arrangement of parts hereinafter described, and particularly pointed out in the claims.

In the accompanying drawings, Figure 1 is a side elevation of the apparatus; Fig. 2, an enlarged detail view of the motor-head and parts immediately associated therewith. Fig. 3 is a front view of Fig. 2. Fig. 4 is a detail plan view. Fig. 5 is a detail view of the fulcrum. Fig. 6 is a detail view showing the manner of supporting the vibrating arm.

The apparatus comprises a vibrating instrument 1, carried by a vibrating arm 4, fulcrumed at 5 to an arm 6, projecting from a head 7, the said head containing an eccentric-pin 8 on a shaft 9, driven by a motor contained within a motor casing or head 10, the said motor being preferably electrically driven and the conducting-wires of which are shown at 11. The pin 8, which is eccentrically arranged on the end of the shaft 9, engages a slot or opening in the upper end of the arm 4 and vibrates the same about the fulcrum 5. The arm is sustained in this vibrating action by a steel plate or link 12, having a pin 13 at its upper end engaging a hole in the front wall 14 of the vibrator-head, the said steel plate having at its lower end a pin 9^x, engaging an opening in the vibrating arm 4 to sustain the same. The arms 4 and 6 are both slotted longitudinally, and the fulcrum 5 is adapted to be adjusted longitudinally of the said arms to vary the throw of the vibrating instrument carried by the vibrator-arm 4. For this purpose the fulcrum comprises besides the collar for the fulcrum proper (marked 5) a flange 15, fitting against the face of the arm 6 and having a collar or projection 16 extending into the slot of the said arm 6, the bolt 2 extending through the fulcrum 5, having a head 17 on its end en-

gaging the back face of the arm 6, the said head having a portion 18 extending into the slot of the arm 6. The bolt on its opposite end is threaded and receives a knurled nut 19, adapted to bear on the end of the fulcrum 5, which projects slightly beyond the face of the vibrating arm 4. By turning this nut the flange 17 and head 18 will be clamped firmly to the arm 6 at any desired point along the slot in the said arm, and the fulcrum 5 will thus be held at any desired point to get the throw of the vibrating instrument, as may be desired, and in all adjustments of the fulcrum the arm 4 will be free to turn about the fulcrum 5, because the nut 19 exercises no binding effect on the said vibrating arm, but only on the end of the fulcrum 5.

At 20 I show a knurled nut mounted on a bolt connected with the motor-casing 10 and passing through the forked support 21, the end of which is provided with a shank 22, extending into a coupling-piece 23, pivoted at 24 to swing horizontally at the end of a flexible arm 25, made up of two members 26 27, pivoted together at 28, so that the said arm may have flexibility in a horizontal plane, the member 27 being suitably supported by a sleeve 29 on a standard 30. The said shank 22 on the fork 21 is provided with a circumferential groove 31, receiving a set-screw 32, having a handle 33, by which the said set-screw 32 may be operated.

It will be seen from the above that if the nut 20 and the set-screw 32 are loosened the vibrator-head will be allowed universal movement, and the head when adjusted into the desired position may be locked in said position or either of the joints which allow the universal movement can be locked by the nut 20 or the set-screw 32 independent of the other joint. For instance, if the set-screw 32 is loosened the fork 21, together with the vibrator-head and the vibrating instrument, can be rotated around a horizontal axis until the depending arms 4 and 6 are brought to an angle of, say, thirty degrees, and then by tightening the set-screw 32 the instrument will be in position to impart a pounding motion to a surface located beneath it. On the other hand, if the

locking-nut 20 is loosened while the set-screw 32 is tightened the operator will be enabled to bring the vibrator-arm 4 into a position parallel with the swinging or flexible arm 25 of the apparatus, and this will be necessary in treating cases where the neck of the patient or the sides of his body must be directly operated on.

It will be seen that the motor in my present apparatus is carried at the outer end of the flexible or swinging arm and direct electrical connection is made thereto and that said motor is directly connected by rigid shafting with the vibrator-arm and said rigid shafting follows the adjustment of the said vibrator-arm. In other words, the said vibrator-head, the motor, the motor-head, and the inflexible shaft between the motor and the vibrator-arm all are movable as one body and are adjustable about the pivot controlled by the lock-nut 20.

The vibrating instrument is attached to the vibrating arm by having the former provided with a screw-threaded extension 35, adapted to receive the instrument thereon, one of which is shown in the form of a ball or sphere.

It will be seen from the above that the shank of the fork forms, substantially, a swiveled or pivotal connection for the said fork, thus allowing the vibrator-head to be turned in a direction at right angles to that allowed by the pivots controlled by the lock-nut 20, and it will be seen, further, that this universal support for the vibrator-head is carried at the end of the flexible arm composed of the members 35 26 and 27.

The connection between the horizontally-disposed support or fork 21 and the flexible arm is a pivoted one in the nature of a swivel, allowing the said support or fork to be turned about its longitudinal axis.

It will be seen from Fig. 1 that the motor-head and vibrator-head are arranged to turn as one body about the horizontal pivots at the outer end of the fork 21, and it will be seen 45 that these pivots are located back from or to one side of the vibrator-head and its vibrating arm. In other words, the vibrating arm is located at a point out beyond the vertical plane of the pivots, about which the vibrator-head may turn.

I claim as my invention—

1. In combination with a vibrator-head, a vibrator-arm, means for vibrating the arm, a link connected with the head and a pin connecting the link with the said vibrator-arm, substantially as described.

2. In combination with a vibrator-arm, means for vibrating the same, a vibrator-head, a link, a pin connection between the said plate and head, and a pin connection between the link and vibrator-arm, substantially as described.

3. In combination, a vibrator-head, a vibrating instrument carried thereby, horizontally-disposed pivots about which the said

head may be turned, said pivots being arranged at right angles to each other, substantially as described.

4. In combination with a flexible arm, a vibrator-head and a universal-joint connection 70 between the said vibrator-head and the end of the flexible arm, substantially as described.

5. In combination, a vibrator-head, a vibrator-arm depending therefrom, a horizontally-disposed pivot about which the head may 75 turn and supporting means, substantially as described.

6. In combination, a vibrator-head, a vibrator-arm depending therefrom, horizontally-disposed pivots at right angles to each 80 other by which the vibrator-head may be turned to set the depending arm in different positions and supporting means, substantially as described.

7. In combination with a vibrator-head, a 85 motor-head, a pivotal support for the motor-head, a vibrator-arm and rigid shafting between the said motor and vibrating arm, said motor and vibrator-head moving as one body about the pivotal point, substantially as described.

8. In combination, a vibrator-head, a depending arm, carried thereby, a pivot about which the head may turn located to one side of the said vibrator-arm whereby the vibrator-arm may be swung into a position below 95 the pivot or may depend vertically at a point out beyond the pivot, substantially as described.

9. In combination with supporting means, 100 a horizontally-extending arm, a vibrator-head, a connection between the said head and horizontally-extending arm including a pivot located at a point to one side of the depending vibrator-arm carried by the vibrator-head, substantially as described.

10. In combination, a vibrator-head, a vibrating instrument carried thereby, a motor-head, a pivotal support for said motor-head, the said vibrator-head being connected with the motor-head at a point out beyond the pivotal point, and means for driving the vibrator-arm from the motor, substantially as described.

11. In combination a vibrator-head carrying a vibrating instrument, a motor connected with the vibrating instrument, a motor-head connected with the vibrator-head, a pivotal support for the said motor-head and a swiveled connection for the said pivotal support, 120 substantially as described.

12. In combination, a support extending horizontally and having a swiveled connection allowing it to be turned about its longitudinal axis, a vibrator-head pivotally supported at 125 the end of the said swiveled support, a vibrating instrument carried by the said head and means for driving said instrument, substantially as described.

13. In combination, a horizontally-extend-

130

ing support having a swiveled connection allowing it to be turned about its longitudinal axis, a motor-head pivotally supported in the end of the said swiveled support, a vibrator-head connected with the motor-head, a vibrating instrument on the said vibrator-head and means for driving the same from the motor, substantially as described.

14. In combination, a vibrator-head, a vibrating arm depending therefrom, a motor-head connected with the vibrator-head, a fork pivotally connected with the motor-head, a swiveled connection for the said fork at its shank and means for supporting the said swiveled connection, substantially as described.

15. In combination with a flexible arm extending horizontally, a horizontally-extending fork swiveled in the end of the said arm, a vibrator-head pivotally connected with the said fork, a vibrating instrument carried by the vibrator-head and means for driving the said instrument, substantially as described.

16. In combination with a horizontal flexible arm, a horizontally-extending fork swiveled at the end of said arm, a motor-head pivoted in the said fork, a vibrator-head connected with the motor-head, a vibrating instrument and connections between the same and the motor carried by the motor-head, substantially as described.

17. In combination with the motor-head, a fork in which the said motor-head is pivotally supported, supporting means for the fork, a coupling pivoted to the said supporting means, the said fork having its shank swiveled in the coupling, a vibrator-head, and a vibrating instrument carried thereby, substantially as described.

18. In combination with a vibrator-head,

horizontally-disposed pivots arranged at right angles to each other for the universal adjustment of the said head, and locking means at the said pivots whereby the said head may be set in fixed relation to either of said pivots, substantially as described.

19. In combination with a horizontally-disposed support, a pivoted or swiveled connection for the said support by which it may be turned around its longitudinal axis, a vibrator-head, a pivotal connection between the same and the said swiveled support by which the head may be turned in a direction at right angles to that permitted by the swiveling action of the said support and locking means for the pivotal and swiveling action, substantially as described.

20. In combination, a vibrator-arm, a head, a link connection between the arm and head, an instrument on the said arm and means for vibrating the arm, substantially as described.

21. In combination a motor-head, a vibrator-head rigidly connected with the motor-head and means for supporting one of the said heads, substantially as described.

22. In combination motor and vibrator heads rigidly connected together and an adjustable arm carrying the said motor-head, substantially as described.

23. In combination a motor-head, a vibrator-head, a rigid shaft between the motor and the vibrator and means for supporting the motor-head adjustably, substantially as described.

In testimony whereof I affix my signature in presence of two witnesses.

CHARLES OWENS.
